G. E. DAGGETT.
 RAILROAD RAIL JOINT.
 APPLICATION FILED JAN. 20, 1902.

NO MODEL.

UNITED STATES PATENT OFFICE.

GEORGE EDWIN DAGGETT, OF HARRISBURG, PENNSYLVANIA, ASSIGNOR TO
THE WEBER RAILWAY JOINT MFG. CO., OF NEW YORK, N. Y., A CORPO-
RATION OF WEST VIRGINIA.

RAILROAD-RAIL JOINT.

SPECIFICATION forming part of Letters Patent No. 728,373, dated May 19, 1903.

Application filed January 20, 1902. Serial No. 90,433. (No model.)

To all whom it may concern:

Be it known that I, GEORGE EDWIN DAGGETT, of Harrisburg, in the county of Dauphin and State of Pennsylvania, have invented 5 a new and useful Improvement in Railroad-Rail Joints, of which the following is a specification.

My improvement specially relates to a railroad-rail joint of a kind which comprises an angle shoe or chair, a bar of packing material adjacent to the upright of the chair, a fish-plate at one side of rail-sections to be united, and another fish-plate upon the opposite side of those rail-sections, all these parts 10 being united by transverse bolts. In such a railroad-rail joint and in others having the same general characteristics expansion and contraction are apt to shift the rail-sections in such a way that instead of forming small 15 gaps between all the rail-sections the spaces become cumulative until large spaces are formed between some of the rail-sections, while comparatively none exist between others.

20 The object of the present improvement is to reduce the cumulation of spaces to a minimum.

This improvement consists in the combination, with various parts forming a rail-joint 25 embodying or resembling the general characteristics described, of bolts having their bodies or portions of their bodies made oval or elliptical in cross-section and applied with the major axis or the larger diameter of the 30 elliptical cross-section in a substantially horizontal plane, so as to substantially fill the openings in the parts which are to be united by the bolts. Thus the bolts will minimize longitudinal movements of the rail-sections.

35 In the accompanying drawings, Figure 1 is a transverse section of a rail-joint embodying this improvement. Fig. 2 is a horizontal section of the same, taken at the plane of the bolts. Fig. 3 is a section of the same taken 40 lengthwise of the rail-sections at the plane of the dotted line 3 in Fig. 2. Fig. 4 is a section of the same taken lengthwise of the rail-sections at the plane of the dotted line 4 in Fig. 2. Fig. 5 is a section of the same taken

lengthwise of the rail-sections at the plane 50 of the dotted line 5 in Fig. 2. Fig. 6 is a section of the same taken lengthwise of the rail-sections at the plane of the dotted line 6 in Fig. 2. Fig. 7 is a section of the same taken lengthwise of the rail-sections at the plane 55 of the dotted line 7 in Fig. 2.

Similar letters of reference designate corresponding parts in all the figures.

A designates an angle shoe or chair of any suitable material having a base a' and an upright a^2 , preferably reinforced at their junctional portions.

B and C are fish-plates of any suitable material and construction arranged upon opposite sides of a rail-section D, which is to be 65 united to another rail-section in line with it.

E designates a bar of packing material, preferably of wood, arranged intermediate of the upright a^2 of the angle shoe or chair A and the fish-plate B.

F designates bolts, of which there may be any suitable number, extending transversely through all the parts named. Each of these bolts has a head e' , an oval or elliptical portion e^2 , adjacent that head and fitting quite 70 closely in an elliptical hole in the upright a^2 of the angle shoe or chair A. The major axis of this elliptical portion e^2 of the bolt and of the elliptical hole in the upright of the shoe-angle is in a horizontal plane. Hence the 75 greatest stiffness or strength of the bolt is in that plane. Beyond the portion e^2 the body of the bolt e^3 is of substantially uniform but smaller diameter and still oval or elliptical, and it passes through a comparatively large 80 hole in the packing-bar E. The portion e^2 of the bolt may enter this hole in the packing-bar, as shown in Fig. 2. This hole in the 85 packing-bar need not be elliptical.

In the fish-plate B is a hole, which may be 90 round and fits quite tightly the wider portion of the body e^3 of the bolt. The hole in the rail-section D may be round. It fits comparatively closely the wider portion of the body e^3 of the bolt.

The fish-plate C has an elliptical hole, which 95 may fit quite closely around the elliptical body e^3 of the bolt. The end portion of the

bolt e^4 is cylindrical and screw-threaded to engage an ordinary nut e^5 .

It will be seen that each bolt will be retained with the major axis of its elliptical portion in horizontal plane, and therefore that its greater cross-section will be disposed horizontally to give the bolt the greater strength for resisting strains incident to expansion and contraction of the rail-section. It will also be seen that the elliptical portions of the bolt fit so closely in the parts with which they are combined as to reduce shifting of rail-sections to a minimum. The fitting of an elliptical portion of each bolt in an elliptical hole in the upright of the angle shoe or chair prevents the turning of the bolt.

What I claim as new, and desire to secure by Letters Patent, is—

1. The combination with adjacent rail-sections and parts applied to opposite sides thereof, of headed bolts passing through all these parts and made oval as to their body portions, said body portions being of different diameters, and round screw-threaded portions at

their outer ends, the larger body portions of said bolts being secured by a correspondingly-shaped hole in one of the parts, so that their widest portions will lie in a horizontal plane and the bolts be prevented from turning.

2. The combination with adjacent rail-sections and parts applied to opposite sides thereof, of bolts passing through all these parts and made oval with body portions of substantially uniform diameter, said bolts being secured with their greatest diameter in a horizontal plane, whereby the spaces between the sides of the bolt and the inside of the bolt-holes in the webs of the rails are reduced in a horizontal plane, to reduce longitudinal movement of the rails.

In testimony whereof I have signed my name to this specification in the presence of two subscribing witnesses.

GEORGE EDWIN DAGGETT.
